Primary Examiner — Barbara Fox*Assistant Examiner* — Lorna M Georges(74) *Attorney, Agent, or Firm* — Kreative IP Management LLC; Fuiyeong Kim**CLAIM**

The ornamental design for a charge connector as shown and described.

DESCRIPTION

FIG. 1 is a front view of a charge connector showing my new design;

FIG. 2 is a rear view thereof;

FIG. 3 is a right side view thereof;

FIG. 4 is a left side view thereof;

FIG. 5 is a top plan view thereof;

FIG. 6 is a bottom plan view thereof;

FIG. 7 is a front, top, and right side perspective view thereof;

FIG. 8 is a rear, bottom, and left side perspective view thereof;

FIG. 9 is a front, right, and bottom side perspective view thereof; and,

FIG. 10 is a rear, left, and top side perspective view thereof. The broken lines shown in the drawings indicate portions of the charge connector that form no part of the claimed design.

1 Claim, 10 Drawing Sheets(56)
